ATOMIZER CONSTRUCTION

Santy M. Croce, Hauppauge, N. Y., assignor to Coty, Inc.,
New York, N. Y., a corporation of Delaware

Application November 6, 1956, Serial No. 620,735

6 Claims. (Cl. 299—88)

This invention relates to atomizers and more particularly to an atomizer of the type which may be simply incorporated or combined with a cap for a perfume bottle. Thus, the preassembled cap-atomizer structure may be attached to the filled bottle so that it serves as an effective closure as well as atomizing means.

The atomizer of this invention is of marked simplicity comprising a minimum number of parts. Its main body is of a structure which eliminates the need of a resilient gasket such as is normally employed in atomizers. Such structure further has a flexibility which enhances the sealing action taking place at its orifices. In addition, the article is rendered most decorative by having a jewel or the like at its upper end. The jewel itself however is not merely decorative since it functions as a locking element, the jewel serving to lock the components of the atomizer together. The invention has other advantages such as will be understood from the following description and drawings in which:

Figure 1 is a vertical cross-sectional view of a combined perfume bottle cap and atomizer as applied to a perfume bottle (broken away in the drawing), the atomizer being in the open position;

Figure 2 is a cross-sectional view as taken along the line 2—2 of Figure 1;

Figure 3 is a view similar to Figure 2 but with the atomizer in the closed position;

Figure 4 is a cross-sectional view as taken along the line 4—4 of Figure 1;

Figure 5 is a view similar to Figure 4 but with the atomizer in the closed position;

Figure 6 is a top perspective view of the atomizer collar for defining the open and closed position of the atomizer; and

Figure 7 is a top plan view of the combined atomizer cap and perfume bottle.

The sealing and atomizing unit referred to collectively as 1, is applied to a bottle 2 containing perfume. The bottle 2 has a threaded neck which is engaged by the cap insert or liner 3, said liner 3 being press fitted into metallic outer cap or shell 4. Cap 4 is formed with a central opening 5. It is through this opening 5 that the body of the atomizer extends and is secured to the top of the bottle neck.

The body 6 of the atomizer is preferably of resilient rubber or plastic such as vinyl or nylon. It is formed with a base or floor flange 7 which is clamped to the lip of the bottle neck when the cap 4 is screwed down. Body 6 is shown as having a central post 8 which is illustrated as being wider at its bottom than at its top although it may assume any desirable form. The upper end of post 8 is terminated in a crown or mouth 9 which is open in its center. Such opening is adapted to receive the locking jewel as will hereinafter be described.

Post 8 is formed with a laterally disposed, vertical passage 10 in which is fitted a downwardly extending tube 11 which functions as a wick or the like. Accordingly, the tube 11 may be fabricated of porous material if de-

2

sired. Passage 10 communicates at its upper end with chamber 12 which may be termed the outlet chamber of the atomizer body. Post 8 is further formed with a transverse passage 13 which is open from one end of the post 8 to the other and terminates in a nozzle 14 disposed in the chamber 12 so that transverse passage 13 communicates with chamber 12. Post 8 is also formed with a short vertical passage 15 which communicates with a short transverse section 16 for the purpose of providing an air vent.

As will be explained hereinafter, the movable elements of the atomizer are rotatable through 90 degrees to provide either the open or closed position thereof. The rotatable portion comprises an arm 17 to one end of which is connected air compression means in the form of a deformable bulb 18. The arm 17 is hollow and extends into the bulb 18 as is conventional. Connected to the other end of the arm is a rigid collar 19 which may be of metal or the like. Collar 19 is formed with an outlet nozzle 20 which may graduate to a smaller diameter at its outlet end as shown. The bottom wall of collar 19 is cut away along an arc 21 as illustrated in Figures 4 and 5, thus providing defining edges 22 and 23 which serve as limits and define the swing of the rotatable section. As an example, arc 21 may be about 150 degrees, thus permitting limited rotation of a limit tongue as will be hereinafter described.

It will be understood that rotation of the arm 17, bulb 18 and collar 19 in relation to the atomizer body 30 6, determines the open and closed positions of the atomizer. However, it has been determined that the relatively soft material of which the atomizer body 6 is fabricated would sometimes interfere with proper positioning of the rotatable structure for accurately controlled open and closed positions. Accordingly, a rigid collar 24 is provided. Collar 24 may be fabricated of rigid plastic or metal. It is provided with a pair of openings 25 which serve to position it angularly upon the flange 7, said flange 7 being formed with protuberances 26 which extend through the openings 25 for this purpose. Collar 24 is formed with a vertical flange 27 which is further formed with an upstanding arcuate tongue 28. Tongue 28, in combination with arcuate cut-out 21 limits and determines the open and closed position of the atomizer.

In an actual embodiment, the arcuate cut-out 21 was about 150 degrees and about $\frac{1}{16}$ " in depth, the same as the height of tongue 28. The extent of arcuate tongue 28 was about 30 degrees. Accordingly, the tongue 28 was permitted a 90 degree revolution within arcuate cut-out 21, such 90 degrees constituting the swing of the rotatable portion and defining the open and closed positions respectively at the ends of such swing.

The atomizer and bottle are assembled by first disposing the collar 24 on the flange 7 and then clamping both of them simultaneously against the lip of the bottle neck by means of the cap 4 as illustrated in Figure 1. Collar 19 is then forced over the upper end of crown 9 and against the vertical flange 27 upon which it comes to rest. Crown 9 is then spread apart and a synthetic jewel or the like 29 is inserted therein. The crown is thus horizontally diametrically spread and is permitted to return to normal position except for the locking influence of the jewel 29. The jewel 29 locks the collar 19 against axial movement and prevents it from becoming disengaged from the post 8 and the entire unit is thus locked in position by the jewel.

In the open position as shown in Figure 1, one edge of arcuate tongue 28 lies against defining edge 22. In this position, pressure upon the bulb 18 will send a stream 70 of air through the hollow interior of arm 17, through transverse passage 13, chamber 12 and outlet nozzle 20. This, of course, will lower the pressure at the top of

passage 10 and, by Venturi action, perfume will be drawn up through the passage 10 and sprayed outwardly as is well understood.

When, however, it is desired to close the atomizer, the bulb 18 and arm 17 are swung 90 degrees until defining edge 23 of arcuate cutout 21 is intercepted by the opposite edge of the arcuate tongue 28. This position is illustrated in Figure 5. When this occurs, the outlet nozzle 20 is blocked by the body of the atomizer as illustrated in Figure 3. Transverse passage 13 is also blocked 10 as is the inner end of the opening of arm 17, so that pressure on the bulb cannot produce any atomizing action.

In the open position of the atomizer, the passages 15 and 16 communicate with a short downward groove 30 15 formed in the wall of collar 19 which serves as an exit vent.

While I have shown and described what I believe to be the best embodiments of my invention, it will be apparent to those skilled in the art that many changes and modifications may be made therein without departing from the spirit and scope of the invention as shown in the appended claims.

What is claimed is:

1. An atomizer for dispensing liquid from a bottle having a neck, said atomizer comprising an atomizer body having dispensing passage means formed therethrough and adapted to be secured to a bottle neck, an air propelling member rotatably surrounding and embracing said body, and means to lock said air propelling member to said body against disassembly therefrom, said locking means comprising a resilient crown formed at the top end of said body and a spreader member removably received in said crown and spreading said crown over said air propelling member to lock said air propelling member in its 25 rotating position.

2. An atomizer for dispensing liquid from a bottle, said atomizer comprising an atomizer body of resilient material and having dispensing passage means formed therethrough and adapted to be secured to a bottle neck, an air propelling member rotatably surrounding and embracing said body, and means to lock said air propelling member against axial movement in respect to said body, said locking means comprising a mouth formed at the top end of said body, and a rigid spreader member seated in said mouth and spreading said mouth from a normal diameter thereof to a larger diameter where it spreads over said air propelling member.

3. An atomizer according to claim 2 and wherein said body is substantially cylindrical, said air propelling member including a collar which rotatably embraces said body, and said rigid spreader comprising a decorative element disposed above said collar, said air propelling member 30

further including air compression means rotating together therewith.

4. An atomizer according to claim 3 and including a rotation limiting stationary collar disposed around said body below said air propelling member collar and on which said air propelling member collar rests, said limiting collar being of rigid material, a tongue formed on said limiting collar, and the lower end of said air propelling member collar having a groove formed therein in which said tongue is slidably received, the extent of said groove in cooperation with said tongue determining the limits of rotation of said air propelling member, one limit of rotation constituting an open position of the atomizer and the other limit of rotation constituting a closed position thereof.

5. An atomizer according to claim 4 and including a horizontal flange integral with said body and constituting a floor therefor, and means on said horizontal flange for maintaining said limiting collar in a predetermined angular position.

6. An atomizer for dispensing liquid from a bottle having a neck, said atomizer comprising a resilient body having a base adapted to rest upon the bottle neck and extending upwardly therefrom in the form of a post, said body having dispensing passage means formed therein, an air propelling member surrounding and rotatably and co-axially embracing said body and having transverse passage means adapted to be aligned with said dispensing passage means of said body upon one limit of rotation of said air propelling member and to be misaligned therewith upon the other limit of rotation thereof, means to effect said two limits of rotation, the rotatability of said air propelling member being in a horizontal plane, and means to lock said air propelling member in respect to co-axial movement on said body, said locking means comprising a crown formed at the top end of said body and extending through a vertical opening through said air propelling member, and a removable rigid insert disposed within said crown and spreading it from a normal diameter thereof to a diameter larger than that of said vertical opening whereby said crown is locked horizontally outwardly of said vertical opening to prevent co-axial displacement of said air propelling member.
